(No Model.)

C. ALVORD.
LOOM.

No. 447,652.

Patented Mar. 3, 1891.

UNITED STATES PATENT OFFICE.

CLINTON ALVORD, OF WORCESTER, MASSACHUSETTS.

LOOM.

SPECIFICATION forming part of Letters Patent No. 447,652, dated March 3, 1891.

Application filed April 19, 1890. Serial No. 348,728. (No model.)

To all whom it may concern:

Be it known that I, CLINTON ALVORD, a citizen of the United States, residing at Worcester, in the county of Worcester and State of Massachusetts, have invented certain new and useful Improvements in Looms; and I do hereby declare that the following is a full, clear, and exact description thereof, which, in connection with the drawings, making a part of this specification, will enable others skilled in the art to which my invention belongs to make and use the same.

My invention relates to looms, and more particularly to the harness and box motions of "open-shed looms."

My invention relates to the harness and box motions of open-shed looms, and more particularly to the cams employed in such motions. In certain forms of harness and box motions in use in open-shed looms levers forming part of the harness and box operating connections are actuated by means of switch-cams, whose switches are controlled by a pattern-chain. In the cam ordinarily known as a "switch-cam" the movements of the switches simply will change the shape of the cam—*i. e.*, from a one-up and three-down cam to a two-up and two-down cam, or some such combination. In other words, the cam is still a cam and will cause the roll or pin traveling in its groove and carried by one of the levers aforesaid to move in and out during each revolution. In a cam embodying my invention, on the contrary, so long as the switches remain in a given position the roll will remain either in or out according to the position of the switches, and if in will move out, or if out will move in, only after the switches have been changed in position, all as will hereinafter be made definitely to appear.

My invention consists, primarily, in a switch-cam of novel construction designed to secure the mode of operation above set forth. It consists, further, in the combination of the cam of the particular construction hereinafter set forth with various associated parts of a loom; and it consists, finally, in an improved shuttle-box motion for a loom, all as will be described hereinafter, and then be pointed out in the claims at the close of the specification.

Referring to the drawings, Figure 1 is a sec-

tional side elevation of my harness-motion detached. Fig. 2 is a sectional side elevation of my box-motion detached. Fig. 3 is a view 55 of a modification of my cam. Fig. 4 is a detail of an oblong shoe used on the cam-lever, the lever being shown in dotted lines. Fig. 5 is a partial detail sectional view on the line W W of the series of shuttle-box-operating 60 cams shown in Fig. 2.

In the accompanying drawings, 1 represents a switch-cam of my peculiar construction fast on the shaft 2.

3 is the harness-jack hung loosely on the 65 pin 4 and carrying the cord 5, which runs over a system of pulleys to the harness-frame. (Not shown.)

6 is the chain-shaft, carrying rolls 7 and tubes 8, which operate the indicating-lever 9, 70 hung loosely on the pin 10.

The harness-jack 3 has an arm 11, carrying a pin 12, which travels in the groove of the cam 1. Said cam is provided with the frog 13, carrying the contact-piece 14, hung loosely 75 on the pin 15. Frog 16 is loosely pivoted at 17, and frog 18 is loosely pivoted at 19. The three frogs 13, 16, and 18 are joined together by the two connectors 20 and 21.

The operation of my harness-motion is as 80 follows: My switch-cam is composed of two concentric grooves and two cam-grooves which cross each other and open into the concentric grooves, all as shown. The spring 22 bears against the arm 23 of frog 18, and in 85 yielding pressure retains the frogs 13, 16, and 18 in the position shown in the full lines, Fig. 1. The pin 12 of the harness-jack 3 is shown in the inner concentric groove, and it is evident that so long as the frogs remain in the 90 position shown in the drawings the rotation of cam 1 will not change the position of the harness-jack. The cam 1 revolves once in every pick of the loom, and the pattern-chain 6 is timed to move the indicating-lever 9 just 95 as the contact-piece 14 moves within reach of the end 24 of lever 9. When the contact-piece 14 approaches the indicating-lever 9, the pattern-chain moves, and if the chain be so built a roll or "riser" will come under lever 100 9, and by the motion of said lever 9 the contact-piece 14 will be depressed, moving frogs 13, 16, and 18 into the dotted-line positions shown in Fig. 1, and the continued rotation of the

cam 1 will cause the pin 12 to run from *a* up the groove *a b c* and into the outer concentric groove of the cam.

It is evident that so long as there are risers 5 on the pattern-chain under the indicating-lever 9 the pin 12 will travel in the outer concentric groove and the harness will remain up; but as soon as a "sinker" appears again on the pattern-chain and allows the indicating-lever 9 to fall back into the position shown in the drawings the pin 12 will run down the groove *d b f* to the inner groove, and will stay there until called up again. Thus it is noted that the "up" or "down" of the harness-jack 15 and corresponding harness at any pick is absolutely controlled by the pattern-chain.

I will now proceed to describe my box-motion. The cams 25, one of which is partly shown in Fig. 2, are of exactly the same style 20 as the cam 1. The pattern-chain 6' and indicating-levers 9' 9" work in the manner described above, and upon the build of the pattern-chain 6' depends the position of the levers which work the shuttle-boxes. The lever 26, loosely hung on pin 4', is provided with the pin 27, which travels in the groove of the first cam, and from the pin 28 runs the connector 29 to the lever 30, pivoted at 31. The lever 32 is also hung on the pin 4', and its pin 33 travels in the groove of the cam immediately in the rear of cam 25. From the pin 34 runs the connector 35 to the lever 36, pivoted at 37 and carrying the sheave 38 on the pin 39. The connector 35 is hidden by the connector 29. The cord 40 runs from lever 30 over sheaves 38 and 40' to the shuttle-boxes. (Not shown.) The levers 30 and 36 work like ordinary compound drop-box levers. The movement of lever 30 will move one box and 40 the movement of lever 36 will move two boxes. In the drawings lever 30 is down and lever 36 is up. Therefore the third shuttle-box is in position.

In Fig. 5 I have shown a partial detail sectional view of the series of shuttle-box-operating cams, and have also shown an outer disk or shield 42, intended to keep the dirt away from the exposed face of the outer cam.

50 In Fig. 3 I have shown my cam with only two frogs, and when using only two frogs it is necessary to use an oblong shoe on the pin of the lever operated by the cam, (see Fig. 4,) to insure that the pin will not run from one 55 of the cam-grooves into the other cam-groove at the point *b*.

I will again call attention to the peculiar

feature of my cam in having two concentric grooves and two cam-grooves which cross each other and open into the concentric grooves, 60 and that by reason of this peculiar construction the harness-jack or box-lever will remain up or down for any number of revolutions of the cam, this being entirely controlled by the "build" of the pattern-chain. 65

It must be understood that I do not confine myself to the exact construction shown in the drawings. Neither do I confine myself to any particular number of frogs interposed at the junction of the grooves of the cam. 70

Having thus described my invention, what I claim as new, and desire to secure by Letters Patent, is—

1. A cam having two concentric grooves and two cam-grooves which cross each other 75 and open into the concentric grooves, and provided with a set of frogs for the purpose of shutting off either of said cam-grooves from said concentric grooves, substantially as described. 80

2. In a loom, the combination, with a pattern-chain, an indicating-lever, and a set of frogs carrying a contact-piece to work with the indicating-lever, of a cam having two concentric grooves, and two cam-grooves 85 which cross each other and open into the concentric grooves, substantially as described.

3. In a loom, the combination, with a harness-jack provided with a pin to work in a cam, of a pattern-chain, an indicating-lever, 90 and a cam provided with a set of frogs carrying a contact-piece to work with the indicating-lever, said cam having two concentric grooves and two cam-grooves which cross each other and open into the concentric 95 grooves, substantially as described.

4. In a loom, the combination, with a series of levers provided with pins for working in a series of cams, a series of box-operating levers, and intermediate connections between 100 said cam-actuated levers and said box-operating levers, of a pattern-chain, a series of indicating-levers, and a series of cams, each cam provided with a set of frogs carrying a contact-piece to work with the indicating-lever, said cams having two concentric grooves and two cam-grooves which cross each other 105 and open into the concentric grooves, substantially as described.

CLINTON ALVORD.
